UNITED STATES PATENT OFFICE.

GEORGE E. ALBIN, OF CORNISH, OKLAHOMA.

AIR-COOLING SYSTEM.

1,267,160.

Specification of Letters Patent. Patented May 21, 1918.

Application filed August 31, 1917. Serial No. 189,219.

To all whom it may concern:

Be it known that I, GEORGE E. ALBIN, a citizen of the United States, residing at Cornish, in the county of Jefferson and State of Oklahoma, have invented new and useful Improvements in Air-Cooling Systems, of which the following is a specification.

This invention relates to air cooling systems for internal combustion engines, the object in view being to dispense with the circulating water now commonly used and also dispense with the usual fan, substituting therefor means for forcing a strong blast or current of cool air through what are now water jackets of the cylinders of the engine. By employing the cooling system hereinafter described and by means of which only air is used for cooling purposes, all danger of freezing in cold weather is eliminated.

A further object of the invention is to provide cooling apparatus of such character, construction and arrangement, that said apparatus may be readily applied to the engines of motor vehicles already in use.

A further object of the invention is to so mount the fan and fan casing of the apparatus that the same is movable bodily toward and away from the fan shaft, being pressed away from the fan shaft by yieldable means, acting to keep the driving belt at a proper driving tension.

With the above and other objects in view, the invention consists in the novel construction, combination and arrangement of parts, herein described, illustrated and claimed.

In the accompanying drawings:—

Figure 1 is a view partly in side elevation and partly in section showing the cooling apparatus in its applied relation to the internal combustion engine of a motor vehicle.

Fig. 2 is a front elevation of the same partly broken away.

Referring to the drawings A designates a multiple cylinder internal combustion engine which is conventionally shown and mounted in the usual position under the hood of a motor vehicle, the latter being designated generally at B. As shown, the engine comprises the usual water outlet manifold 1, and upper water connections 2, the latter communicating with the upper portion of the radiator 3. 4 designates the usual bottom water connection. It is to be understood however that no water is used

under the improved system, the parts 1, 2 and 4 being used as air conduits.

In carrying out the present invention, I employ an air blast fan designated generally at C, the same comprising a fan proper designated at 5 in the form of an Archimedean screw or in other words a fan having a continuous spiral blade. The fan 5 is mounted in a casing comprising a main cylindrical portion 6 having an internal diameter slightly greater than the external diameter of the fan 5. The casing also comprises a frusto-conical or tapering discharge portion 7 to which the usual flexible connection or hose 4 is fastened. The contracting end portion 7 of the casing forms a velocity increasing chamber beyond the end of the fan 5. The fan comprises a central shaft 8 which is journaled in bearings 9 in the casing 6. Said shaft projects beyond one end of the casing where it has fast thereon a small pulley or belt wheel 10. Around the wheel 10 passes a driving belt 11, the latter also passing around and being driven by a belt pulley 12 fast on the usual fan shaft 13 of the motor. From the fan pulley 14 with which the engine is already provided, a second belt 15 passes around the lower fan pulley 16 which is also found on the present motor. Thus the shaft 8 of the fan 5 is driven from the engine shaft 17.

The fan casing is mounted for movement toward and away from the shaft 13 by employing a supporting arm 18 which is connected by a pivot joint 19 to a bracket 20 secured to one side of the engine as indicated in the drawings. At its other end, the arm 17 is shown as having a band or strap 20 which encircles and carries the fan casing 6. A spring 21 is interposed between the arm 18 and a lug or bracket 22 secured in any suitable way to the engine frame. Said spring 21 serves to press the arm 18 and consequently the casing 6 away from the shaft 13 and thereby keeps the belt 11 tight, compensating for any stretching of said belt.

From the foregoing description taken in connection with the accompanying drawings it will now be seen that by arranging a high speed blast fan in the position shown and in the relation to the engine specified, and by providing the fan casing with a velocity increasing chamber, a strong and continuous blast or current of air is forced through all of the jackets of the cylinders,

thus maintaining the cylinder walls in a cool condition and at the same time eliminating all danger of freezing in cold weather. No adjustment is required for the 5 belt 11 as it is maintained under the proper tension by means of the spring 21. Furthermore the air cooling apparatus may be used in conjunction with engines already in use. The apparatus is also adapted to be installed 10 at the time of the manufacture of the motor vehicle.

I claim:—

1. The combination with an internal combustion engine, of an air blast fan casing 15 embodying a cylindrical portion and a frusto-conical velocity increasing chamber, an air blast fan rotatable in said casing and comprising a central shaft journaled in the fan casing, a pivotally mounted support 20 carrying said fan and its casing, belt pulleys on the fan shaft and the engine shaft, intermediate belt pulleys, and driving belt connections between said pulleys, the discharge

end of the fan casing being flexibly connected with the jackets of the engine and yieldable means for pressing the casing support 25 away from the fan shaft.

2. The combination with an internal combustion engine, of an air blast fan embodying a cylindrical portion and a frusto-conical velocity increasing chamber, an air blast fan rotatable in said casing and comprising a central shaft journaled in the fan casing, belt pulleys on the fan shaft and the engine shaft, intermediate belt pulleys, driving belt connections between said pulleys, the discharge end of the fan casing being flexibly connected with the jackets of the engine, said fan casing being mounted for movement toward and away from the engine, and yieldable means interposed between the fan casing and engine and acting 40 as a belt tightener.

In testimony whereof I affix my signature.

GEORGE E. ALBIN.
